UNITED STATES PATENT OFFICE.

ALBERT D. CROSSLEY, OF SOUTH NORWALK, CONNECTICUT, ASSIGNOR OF FORTY-NINE ONE-HUNDREDTHS TO JAMES H. CROSSLEY, OF BRIDGEPORT, CONNECTICUT.

TROLLEY-POLE BASE.

SPECIFICATION forming part of Letters Patent No. 736,942, dated August 25, 1903.

Application filed March 4, 1903. Serial No. 146,067. (No model.)

To all whom it may concern:

Be it known that I, ALBERT D. CROSSLEY, a citizen of the United States, residing at South Norwalk, county of Fairfield, State of Connecticut, have invented a new and useful 5 Trolley-Pole Base, of which the following is a specification.

My invention relates to trolley-pole bases, and has for its object to simplify and cheapen 10 their construction, to greatly improve their general operation, to reduce the cost of maintenance, and to avoid waste of current, as it is rendered impossible to charge either the base or the pole.

15 With these and other objects in view the invention consists in certain constructions and in certain parts, improvements, and combinations, which will be hereinafter described and then specifically pointed out in the claims 20 hereunto appended.

In the accompanying drawings, forming part of this specification, Figure 1 is a side elevation of my novel trolley-pole base as in use; Fig. 2, a plan view corresponding therewith; and Fig. 3 is a view, partly in elevation and partly in section, from a point of view at right angles to Fig. 1, the pole and connections to the base being omitted.

10 denotes the body, which is adapted for 30 attachment to a car; 11, the lower contact-plate; 12, the upper contact-plate, and 13 the top plate. The body and top plate are made of iron and the two contact-plates of copper or high-grade bronze.

35 14 denotes a central opening extending through the body, both contact-plates, and the top plate. The top plate and contact-plates are secured to the body in such a manner as to leave the upper contact-plate and 40 the top plate free to rotate upon the lower contact-plate, as by means of a bolt 15, extending through an insulating-sleeve 16 in the central opening. This bolt is engaged above the top plate by a nut 17, an insulating-washer 18 being interposed between the nut and the top plate. The lower contact-plate is held against rotation on the body by 45 any suitable connection 19, as a projection upon one part and a corresponding recess in 50 the other part. The upper contact-plate is

attached to the top plate, so that the two will oscillate together, by a similar connection 20. The upper contact-plate oscillates freely on the lower contact-plate. The entire surfaces of the two plates may bear upon each other, 55 or, preferably, a recess 21 is formed in the upper contact-plate, which may be packed with graphite or other suitable lubricating material, the bearing consisting of a circular flange 22 on the face of the upper contact-plate at the edge. The lower contact-plate is provided with binding-posts 23, from which electrical connections (not shown) may extend to the motor, and the upper contact-plate is provided with binding-posts 24, from which 60 electrical connections (not shown) may extend up through the pole to the trolley. (Not shown.)

37 denotes insulating sheets or plates interposed, respectively, between the lower contact-plate and the body and the upper contact-plate and the top plate. I thereby insure that the current received at the binding-posts of the upper contact-plate will pass from the binding-posts of the lower contact-75 plate to the motor without loss, neither the pole nor any portion of the base except the contact-plates being in the circuit.

An important saving is effected in the cost 80 of maintenance, as the wear is almost entirely upon the contact-plates, in which I have reduced friction and wear to the minimum by providing the lubricating-recess 21 in the upper contact-plate. When the contact-plates wear sufficiently to interfere with 85 their perfect operation, nut 17 may be unscrewed, which will permit the top plate to be removed and either or both of the contact-plates to be removed and new ones substituted in their stead.

25 denotes a pole the lower end of which is firmly seated in a socket 26, which is hinged to the top plate, as at 27. The socket is provided on opposite sides with ears 28, to which eyes 29 at the inner ends of rods 30 are pivoted, as at 31.

32 denotes eyes which are pivoted to the top plate, as at 33. The rods are shown as curving outward and then as extending backward through eyes 32 and through a cross-piece 34, 100

which is secured at the rear ends of the rods by nuts 35, engaging threads upon the rear ends of the rods. Compression-springs 36, surrounding the rods, bear against the ends 5 of the cross-piece and against eyes 32. It will be noted that the ears to which the rods are pivoted extend considerably above the pivotal point of the socket to the top plate, the parts being so proportioned and arranged 10 that the compression of the springs will be greatest when the pole is at approximately an angle of forty-five degrees to the plane of the base, so that the entire power of the springs will be exerted to hold the trolley in 15 contact with a wire, (not shown;) but should the trolley slip off the wire the force exerted by the springs would grow weaker instead of stronger as the pole swings upward from its normal position—that is, at an angle of forty- 20 five degrees, more or less, to the plane of the base. This construction prevents the pole from being thrown upward to a vertical position with great violence, as when extension-springs are used.

25 Having thus described my invention, I claim—

1. A trolley-pole base comprising a body, a lower contact-plate secured thereto, an upper contact-plate adapted to oscillate on the lower 30 contact-plate, a top plate for the attachment of a pole which is secured to the upper contact-plate and insulation between the contact-plates and the other parts of the base, so that in use the contact-plates only are in the circuit.
- 35 2. A trolley-pole base comprising a body, a lower contact-plate secured thereto, an upper contact-plate adapted to oscillate on the lower contact-plate and provided with a lubricating-recess, a top plate for the attachment of the pole which is secured to the upper contact-plate and insulation between the contact-plates and the other parts of the base, so that in use the contact-plates only are in the 40 circuit.
- 45 3. A trolley-pole base comprising a body, adapted for attachment to a car, a lower contact-plate secured to the body and insulated therefrom, an upper contact-plate adapted to oscillate on the lower contact-plate, binding posts on said contact-plates and a top plate for the attachment of a pole which is secured to the upper contact-plate and is insulated therefrom.
- 55 4. A trolley-pole base comprising a body, a lower contact-plate secured thereto, an upper contact-plate adapted to oscillate on the lower contact-plate, a top plate for the attachment of a pole which is secured to the upper contact-plate, a central opening 60 through the base, contact-plates and top plates, an insulating-sleeve in said opening,

a bolt extending through said sleeve whereby the parts are secured together, a nut on said bolt and insulation between the body and the 65 lower contact-plate and between the top plate and the nut and upper contact-plate.

5. In a trolley-pole base the combination with an oscillating top plate, eyes pivoted thereto and a pole-socket hinged thereto, of 70 rods pivoted to the pole-socket and extending backward through the eyes, a cross-piece at the rear ends of the rods and compression-springs bearing against the cross-piece and the eyes and acting to retain the pole-socket 75 in the operative position.

6. In a trolley-pole base the combination with an oscillating top plate, eyes pivoted thereto and a pole-socket hinged thereto and having ears extending above the pivotal 80 point to the base, of rods pivoted to said ears and extending backward through the eyes, a cross-piece at the rear ends of the rods, and compression-springs bearing against the cross-pieces and the eyes whereby the socket 85 is normally held in the operative position, the force exerted by the springs being reduced when the socket swings upward past the operative position.

7. In a trolley-pole base the combination 90 with a body, a lower contact-plate secured thereto, an upper contact-plate adapted to oscillate on the lower contact-plate, a top plate secured to the upper contact-plate, eyes pivoted to the top plate and insulation 95 between the contact-plates and the other parts of the base, of a pole-socket hinged to the top plate, rods pivoted to the pole-socket and extending backward through the eyes, a cross-piece at the rear ends of the rods and compression-springs bearing against the 100 cross-piece and the eyes, substantially as shown, for the purpose specified.

8. In a trolley-pole base the combination with a body, upper and lower contact-plates 105 and a top plate, said contact-plates being secured respectively to the body and the top plate, and insulation between the contact-plates and the other parts of the base, of eyes 110 and a pole-socket pivoted to the top plate, 110 ears on the pole-socket extending above the pivotal point to the base, rods pivoted to the ears and extending backward through the eyes, a cross-piece at the rear ends of the rods and compression-springs bearing against 115 the cross-piece and the eyes, substantially as shown, for the purpose specified.

In testimony whereof I affix my signature in presence of two witnesses.

ALBERT D. CROSSLEY.
